UNITED STATES PATENT OFFICE.

JOSEPH R. TORREY, OF WORCESTER, MASSACHUSETTS.

RAZOR-STROP.

SPECIFICATION forming part of Letters Patent No. 295,840, dated March 25, 1884.

Application filed December 27, 1883. (No model.)

To all whom it may concern:

Be it known that I, JOSEPH R. TORREY, a citizen of the United States, residing at Worcester, in the county of Worcester and State of Massachusetts, have invented certain new and useful Improvements in Razor-Strops, of which the following is a specification, reference being had therein to the accompanying drawings.

- 10 My invention relates to that class of razor-strops having stropping-belts, the tension of which is regulated by adjustable tightening-plates; my object being to cheapen the manufacture of such plates, and at the same time produce plates of such construction that the rigid wooden bodies of the strops will be less weakened by the holes entered by the projecting pins or lugs of the plates than by the forms of tightening-plates heretofore in use.
- 15 I accomplish this object by striking out the pins or lugs (which enter holes in the end of rigid bodies of the strops and thus serve to prevent the rotation of the tightening-plates with their adjusting-screws) from the body of the plates, thus leaving the said pins or lugs integral with the bodies of the plates. In thus striking out these lugs, one is left connected with the plate near one corner thereof, and the other is left connected near the corner 20 diagonally opposite, both of the lugs being thus in different horizontal planes from each other, and also from the threaded hole in the plate through which the adjusting-screw passes. From this construction it follows that the holes in the end of the wooden body of the strop, entered by the said lugs and screw, will 25 all be in different planes relative to the grain of the wood, and said body will, therefore, be less weakened by said holes than where the 30 holes for the pins or lugs of the plate and the hole for the adjusting-screw are all in the same horizontal or vertical plane across the end of the strop, as in the construction heretofore generally in use.
- 35 In the drawings, Figure 1 is a side view of a strop embodying my invention. Fig. 2 is a transverse section of the same, on the line 22, Fig. 1; and Fig. 3 is a detail perspective view of my improved tightening-plate.
- 40 A indicates the rigid wooden body of the

strop. B is the handle, having a screw-threaded shank, b; and C is the stropping-belt, passing over a bridge-piece, c, at the outer end of the strop and the tightening-plate D at the handle end. The plate D is 5 provided with a threaded hole, d, through which the shank b of the handle B passes into the body A, and with pins or lugs d' arranged diagonally opposite to each other on the plate, as clearly shown in Fig. 3, said pins or lugs 60 being preferably struck out from the body of the plate. These pins or lugs enter holes in the end of the body A, and prevent the rotation of the tightening-plate with the screw-shank b when the handle is turned to adjust 65 the tension of the belt. These pins or lugs, formed as above described, take the place of pins which have heretofore been riveted to the plate, my improved plate, with struck-out lugs, being much cheaper as well as better 70 than the tightening-plates heretofore generally in use.

While it is deemed preferable to leave the struck-out lugs connected to the body of the plate near the diagonally opposite corners 75 thereof, the object of this arrangement may be in a measure attained by leaving both of the lugs connected to the same side or end of the plate near the corners thereof, this latter arrangement bringing the lugs out of line from 80 the threaded hole in the center of the plate. A single struck-out lug, left connected to the body of the plate near one corner thereof, will also serve a very good purpose, but two are 85 obviously better.

It will be understood that my improved tightening-plate may be used in connection with other forms of strops than that herein shown—as, for example, to strops the rigid bodies of which are made concave under the 90 belt, or to the form of strop shown by Patent No. 288,389.

Having thus described my invention, I claim as new and desire to secure by Letters Patent—

1. A tightening-plate for razor-strops having projecting pins or lugs arranged diagonally opposite to each other on the body of the plate, substantially as described. 95
2. A tightening-plate for razor-strops having projecting pins or lugs struck out from 100

the body of the plate and arranged diagonally opposite to each other, substantially as described.

3. The combination of the body A, the handle B, having the screw-threaded shank b, the stropping-belt C, and the tightening-plate D, having the diagonally-arranged projecting pins or lugs d', struck out from the body of the plate, and the threaded hole d, substantially as described.

4. A tightening-plate for razor-strops hav-

ing projecting pins or lugs struck out from the body of the plate and connected with said body near the corners thereof, substantially as set forth.

In testimony whereof I affix my signature in presence of two witnesses.

JOSEPH R. TORREY.
